UNITED STATES PATENT OFFICE.

CHARLES MAGEE, OF BROOKLYN, NEW YORK, ASSIGNOR TO THE BIGELOW CARPET COMPANY, OF CLINTON, MASSACHUSETTS.

DESIGN FOR A CARPET.

Specification forming part of Design No. 11,282, dated July 8, 1879; application filed May 20, 1879.
[Term of patent 3½ years.]

To all whom it may concern:

Be it known that I, CHARLES MAGEE, of Brooklyn, Kings county, New York, have invented a new and original Design for a Carpet, of which the following is a specification.

This invention relates to a new and original design for a carpet, oil-cloth, or similar fabric.

It consists in the new ornamentation of the carpet by floral groups, as hereinafter more fully pointed out.

The accompanying drawing represents a face view of my newly-invented design.

In the drawing, the letters A, B, C, and D represent four floral groups arranged around a common center. In the group A a rose, *a*, is conspicuous. This group contains, furthermore, the representation of several smaller flowers, as shown. The groups B and C are also composed of flowers and leaves, while the group D is composed of fern-leaves, and is ornamented by small dots and flowers. Upon the background of the carpet are furthermore represented a series of diagonal stripes, *b*, that are provided with rectangular projections, said projections extending in the same direction from the several stripes, *b*. The stripes *b* are terminated at one end by a straight bar, *f*, from which an ornamented flower, *g*, extends upwardly. Between the groups A and B are represented, in rectangular parallel panels, a series of fern-shaped ornaments, *h*. *i* is a

similar group placed at right angles to the group *h*. On the background of the carpet is furthermore represented a rich group of foliage, *e*, which partly extends between the groups A and C, and other smaller designs of various description. The design is made in suitable colors.

I claim—

1. The design for a carpet, consisting of the groups A, B, and C, substantially as shown.
2. The design for a carpet, consisting of the groups C, D, and B, substantially as shown.
3. The design for a carpet, consisting of the groups A B C D, substantially as shown.
4. The design for a carpet, consisting of the groups A B C D, and of the parallel bars *b*, substantially as shown.
5. The design for a carpet, consisting of the stripes *b*, having rectangular projections, and of the bar *f*, substantially as shown.
6. The design for a carpet, consisting of the stripes *b*, bar *f*, and flower *g*, substantially as shown.
7. The design for a carpet, consisting of the groups A, *e*, and C, substantially as shown.
8. The design for a carpet, consisting of the groups A B C D *e*, the stripes *b*, bar *f*, flower *g*, and groups *h i*, substantially as shown.

CHARLES MAGEE.
